UNITED STATES PATENT OFFICE.

JESSE HALL, JR., OF PHOENIXVILLE, PENNSYLVANIA, ASSIGNOR TO THE PHOENIX IRON COMPANY, OF SAME PLACE.

ROTARY PUDDLING-FURNACE.

SPECIFICATION forming part of Letters Patent No. 295,751, dated March 25, 1884.

Application filed June 22, 1883. (No model.)

To all whom it may concern:

Be it known that I, JESSE HALL, Jr., a citizen of the United States, and a resident of Phoenixville, Chester county, Pennsylvania, have invented certain Improvements in Rotary Puddling-Furnaces, of which the following is a specification.

My invention consists of certain improvements, fully described hereinafter, in the movable flue-sections between a fixed flue and the outlet end of a rotary puddler.

In the accompanying drawings, Figure 1, Sheet 1, is a view, mainly in section, of a rotary puddler, part of a furnace, and my improved flue structure for carrying off the products of combustion to a fixed chimney; and Fig. 2, Sheet 2, an end view of Fig. 1, looking in the direction of the arrow.

The rotary puddler A, which is supported on wheels carried by a truck, A', in a manner described in another application for a patent, does not differ materially from ordinary rotary puddlers. There is the usual outer shell, a, the inner casing, b, the water-space c between the two, and the lining d of refractory material. The inlet-opening e of the puddler is surrounded by a ring, f, with which coincides a ring, f', surrounding the outlet g of the furnace B, and the outlet-opening h of the puddler is surrounded by a ring, j, coinciding with a ring, j', at the entrance i of the flue structure C. My invention relates to this structure, the manner of introducing water into the space between the two casings of the puddler, of moving the latter endwise and free from frictional contact with the furnace, and the mechanism for rotating the puddler and moving it away from or introducing it between the furnace and flue structure being described in another application for a patent. The permanent elevated chimney D is built on transverse beams m m, secured to longitudinal beams n, which are supported by columns p; or the chimney may be built on any other available supports or frame-work. The flue structure C is composed of the outer casing, q, the inner casing, t, and the refractory lining r, water being introduced into and circulating within the space between the two casings. The flue C is pivoted to or loosely suspended from

the chimney-supporting structure, links K K', as shown in Fig. 2, being in the present instance used for this purpose, the links being adapted to hooks s s, one of which is secured to each edge of the flue. The links are preferably inclined, as shown, the threaded ends of the upper links being provided with nuts, by turning which the flue can be so adjusted that its entrance i may coincide with the outlet-opening of the puddler. To a suitable foundation are secured standards E E, through which pass set-screws F F, carrying at their ends plates x, which, by adjusting the screws, are caused to bear against the rear of the flue structure, so that the front end of the latter can be moved as close to the rear end of the puddler as the desired free rotation of the same will permit. The suspension-links are attached to the flue structure at such a point that when it is relieved from the pressure of the screws it will recede from the end of the puddler and permit the same to be withdrawn from between the furnace and flue structure. Thus, if the hooks to which the links are connected are at the point y, the preponderance of the front portion of the structure will induce the same to move away from the end of the puddler when the flue is relieved from the pressure of the screws. The upper end of the flue structure should be as close to the lower end of the fixed chimney as the required slight movement of the flue structure will permit. At the back of the said structure is an opening provided with a suitable door, in which is a peep-hole for the inspection of the interior of the puddler.

I am aware that a movable flue-section has been combined with and interposed between the outlet end of a rotary puddler and a fixed flue or chimney. This, therefore, I do not claim; but

I claim as my invention—

1. The combination of the puddler and a fixed vertical chimney, open at the bottom, with the pivoted or suspended flue structure C, having an opening at the top communicating with the said chimney, and a lateral opening communicating with the outlet of the puddler, all substantially as set forth.

2. The combination of the fixed chimney, 100

open at the bottom, the rotary puddler, and the flue structure pivoted or loosely suspended beneath the chimney at *y*, so that there shall be a preponderance of the structure tending to 5 keep it away from the puddler, with devices for forcing the lower portion of the structure against the outlet end of the puddler, all substantially as specified.

In testimony whereof I have signed my name to this specification in the presence of two sub- 10 scribing witnesses.

JESSE HALL, JR.
